UNITED STATES PATENT OFFICE.

STEPHEN PALMER, OF LANSINGBURG, NEW YORK.

DESIGN FOR A SASH-CORD-GUIDE FACE-PLATE.

SPECIFICATION forming part of Design No. 19,245, dated July 30, 1889.

Application filed July 1, 1889. Serial No. 316,239. Term of patent 7 years.

To all whom it may concern:

Be it known that I, STEPHEN PALMER, a citizen of the United States, residing at the village of Lansingburg, county of Rensselaer, and State of New York, have invented and produced a new and original Design for Sash-Cord-Guide Face-Plates, of which the following is a specification, reference being had to the accompanying drawing, forming a part thereof, and showing by a single figure a plan view of my newly-designed face-plate.

The leading feature of my design is found in the outer contour of the plate, which contour describes an elongated figure having 15 straight parallel sides terminating in segments. Such segments are united by an intersecting segment greater than a semicircle, one at each end of the figure. The outer contour segments are all described with the same radius from centers located in a straight line drawn longitudinally through the center 20 of the figure. The central part of the figure is provided with an elongated aperture and the end segments with small circular apertures. The contour line on one side of the

figure is broken by a series of small angular offsets, so located as to form a straight row of equidistant offsets, those at the ends of the row appearing upon one side of the respective end segments, and those located intermediate of the row upon one of the straight parallel sides of the figure. 30

Referring to the drawing, A A' are the straight parallel lines which terminate in the segments B'. 35

C C' are the end segments which intersect the segments B'.

D D are the angular offsets in the outline formed by one side of the plate.

A² is the central elongated aperture, and C² 40 the circular apertures in the end segments.

What I claim as new is—

The design for a sash-cord-guide face-plate herein shown and described.

In testimony whereof I have hereunto set 45 my hand this 29th day of June, 1889.

STEPHEN PALMER.
